UNITED STATES PATENT OFFICE.

WILLIAM M. MATTEOLI, OF COVINGTON, KENTUCKY.

FOCUSING DEVICE FOR LAMPS.

1,244,880.

Specification of Letters Patent. Patented Oct. 30, 1917.

Application filed February 3, 1917. Serial No. 146,332.

To all whom it may concern:

Be it known that I, WILLIAM M. MATTEOLI, a citizen of the United States of America, and resident of Covington, in the county of 5 Kenton and State of Kentucky, have invented a new and useful Improvement in Focusing Devices for Lamps, of which the following is a specification.

Because of the great degree of variation 10 of the position of the filaments relatively to the center of electric bulbs, it has been found necessary to provide means for positioning the filaments properly with relation to the focal center of the parabolic reflectors usually employed in automobile lamps. Such devices as have been provided heretofore, either are too expensive to manufacture or do not economize in the space occupied by them.

20 An object of my invention is to produce a focusing device for automobile lamps, which will occupy less space and which will be cheaper to manufacture than other focusing devices known to me.

25 This and other objects are attained in the focusing device described in the following specification and illustrated in the accompanying drawings, in which:

30 Figure 1 is a fragmental vertical section of a lamp body and reflector having a focusing device embodying my invention, mounted therein.

35 Fig. 2 is a fragmental horizontal section of a lamp having a focusing device embodying my invention, located therein.

40 Fig. 3 is a fragmental front elevation of my improved focusing device in position in a reflector shown fragmentally, the lamp bulb being removed.

45 My improved focusing device consists of a shell 4 adapted to contain the lamp bulb 5, a sleeve 6 surrounding the shell, a ratchet 7 for retaining the sleeve in adjusted positions, a device 8 for adjusting the sleeve and mechanism 9 operatively connecting the shell and the sleeve for transforming rotary motion of the sleeve into reciprocatory motion of the shell. Shell 4 is of the usual construction, being the body of the usual 50 connector provided for the shank 10 of the bulb 5. This shell is slotted in the usual manner at diametrically opposite points 11 and 12 to receive the bulb securing pins 13 provided on the shank 10 of the bulb. At 55 right angles to these slots and diametrically opposite to one another, are additional slots

14 and 15, these slots being provided to receive reflector lugs 16 and 17 respectively, which form keys upon which the shell 4 may reciprocate, but which prevent rotation of the shell. Located between the body 18 and reflector 19 of the lamp, is the sleeve 6 which surrounds the shell 4 and upon which it may be rotated. This sleeve is provided with one or more slots 20 which are formed spirally thereon and which co-operate with pins or screws 21 secured to the shell 4. By rotating the sleeve upon the shell, the pins 21 co-operating with the slots 20, cause the shell to reciprocate backwardly or forwardly to focus the filament 22 of the bulb 5, properly with relation to the focal center of the reflector 19. In order to permit rotatory movement of the sleeve and to avoid injuring the wire 23 through which current is delivered to the lamp bulb 5, I have provided an enlarged spiral slot 24 which permits of the sleeves being rotated without coming into contact with the wire. At its end adjacent to the body 18 of the lamp, the shell is provided with a knurled member 25 which is secured to a pin 26 rotatively mounted in the body portion. Located between knurled member 25 and body 18 of the lamp and secured thereto is a spring 27 having its end looped and bent into engagement with the knurled surface of member 25. This construction permits of the sleeve being rotated in either direction, but acts to retain the sleeve against 75 rotation when properly adjusted. Pin 26 extends through the body 18 and has secured at its outer end a knurled thumb nut or handle 28, by means of which pin 26 may be rotated. By this construction the sleeve 80 is held against forward or backward movement, but is permitted to be rotated, thus acting to project or retract the shell with relation to the reflector 19, the shell having reciprocatory movement only because of its 85 connection with the lugs 16 and 17 of the reflector. If desired, the knurled thumb nut 28 may be eliminated, pin 26 alone being employed to focus the lamp properly, the pin being provided with a slot 29 to receive 90 the blade of the screw driver to effect its rotation.

95 In my improved construction it will be seen that the sleeve and the mechanism by means of which it communicates reciprocation to the shell 4 of the lamp connector, occupies no more room between the body 100 and reflector than the shell 4 occupies in the 105 prior art lamp, the sleeve 6 being of the same diameter as the shell 4.

18 and the reflector 19 of the lamp, than would be required ordinarily by the connector in which the lamp bulb 5 is mounted. Such a construction is highly desirable in 5 that the body 18 may be comparatively shallow as compared to the bodies of lamps employing other focusing devices. This not only cheapens the construction of the lamp by eliminating a certain amount of material 10 necessary to produce the deeper body, but it also eliminates certain manufacturing operations necessary to produce bodies of extreme depth.

Having thus described my invention, what 15 I claim is:

- 15 1. A focusing device for lamps having a body and a reflector mounted therein, consisting of a lamp connector reciprocally mounted in the reflector of the lamp, a 20 sleeve located between the body and reflector of the lamp, rotatively mounted upon the connector and having means for reciprocating the connector when the sleeve is rotated.
- 25 2. A focusing device for lamps having a body and a reflector mounted therein, consisting of a lamp connector reciprocally mounted in the reflector of the lamp, a 20 sleeve located between the body and reflector of the lamp, rotatively mounted on the connector and having means for reciprocating the connector when the sleeve is rotated, and means located exteriorly of the body, adapted to rotate the sleeve.
- 35 3. A focusing device for lamps having a body and a reflector mounted therein, consisting of a lamp connector reciprocally mounted in the reflector of the lamp, a pin 40 mounted on the connector, and a sleeve located between the body and reflector of the lamp, rotatively mounted on the connector and having a spiral slot for coöperation with the pin for reciprocating the connector when the sleeve is rotated.
- 45 4. A focusing device for lamps having a body and a reflector mounted therein, consisting of a lamp connector reciprocally mounted in the reflector of the lamp, a pin 50 mounted on the connector, a sleeve located between the body and reflector of the lamp, rotatively mounted on the connector and having a spiral slot for coöperation with the pin, and means located exteriorly of the body adapted to rotate the sleeve.
- 55 5. A focusing device for lamps having a body and a reflector mounted therein, consisting of a lamp connector reciprocally mounted in the reflector of the lamp, a sleeve 60 located between the body and reflector of the lamp, rotatively mounted on the connector and having means for reciprocating the connector when the sleeve is rotated, and means located exteriorly of the body, adapted to rotate the sleeve, said last mentioned 65 means consisting of a pin extending through

the body of the lamp and accessible for rotation exteriorly of the lamp.

6. A focusing device for lamps having a body and a reflector mounted therein, consisting of a lamp connector reciprocally 70 mounted in the reflector of a lamp, a pin mounted on the connector, a sleeve located between the body and reflector of the lamp, rotatively mounted on the connector and having a spiral slot for coöperation with the pin for reciprocating the connector when the sleeve is rotated, and means located exteriorly of the body, adapted to rotate the sleeve and consisting of a pin extending through the body of the lamp, connected 75 with the sleeve, and accessible for rotation with the sleeve, and accessible for rotation exteriorly of the lamp.

7. A focusing device for lamps having a body and a reflector mounted therein, consisting of a lamp connector reciprocally 80 mounted in the reflector of a lamp, a pin mounted on the connector, a sleeve located between the body and reflector of the lamp, rotatively mounted on the connector and having a spiral slot for coöperation with a 85 pin mounted on the connector, and a ratchet attached to the sleeve, adapted to retain the sleeve in adjusted positions.

8. A focusing device for lamps having a body and a reflector mounted therein, consisting of a lamp connector reciprocally 90 mounted in the reflector of the lamp, a pin mounted on the connector, a sleeve located between the body and the reflector of the lamp, rotatively mounted on the connector 95 and having a spiral slot formed therein for coöperation with the pin of the connector, a ratchet secured to the sleeve, adapted to retain the sleeve in adjusted positions, and means located exteriorly of the body, adapted 100 to rotate the sleeve.

9. A focusing device for lamps having a body and a reflector mounted therein, consisting of a lamp connector reciprocally 110 mounted in the reflector of the lamp, a pin mounted on the connector, a sleeve located between the body and the reflector of the lamp, rotatively mounted on the connector and having a spiral slot for coöperation with the pin of the connector for reciprocating 115 the connector when the sleeve is rotated, a ratchet attached to the sleeve, and a spring attached to the lamp for coöperation with said ratchet, adapted to retain the sleeve in adjusted positions.

10. A focusing device for lamps having a body and a reflector mounted therein, consisting of a lamp connector reciprocally 120 mounted in the reflector of the lamp, a pin mounted on the connector, a sleeve located between the body and reflector of the lamp, rotatively mounted on the connector and having a spiral slot formed therein for co-operation with the pin of the connector, a ratchet attached to the sleeve, a spring at- 125

tached to the lamp for coöperation with the ratchet, adapted to retain the sleeve in adjusted positions, and means located exteriorly of the body, adapted to rotate the 5 sleeve.

11. In combination, a lamp reflector and a focusing device for lamps mounted therein, consisting of a lamp connector having a longitudinally extending slot formed 10 therein, and a lug formed on the reflector adapted to coöperate with the slot to permit reciprocation of the connector.

12. In combination, a lamp body, a lamp reflector mounted therein, a lug formed on

the reflector, a lamp connector reciprocally 15 mounted in the reflector and having a longitudinally extending slot for coöoperating with the lug, and a sleeve located between the body and the reflector, rotatively mounted upon the connector and having means for 20 reciprocating the connector when the sleeve is rotated.

In testimony whereof, I have hereunto subscribed my name this 26th day of January, 1917.

WILLIAM M. MATTEOLI.
